US0D1103624S

(12) United States Design Patent (10) Patent No.: US D1,103,624 S
(45) Date of Patent:  Dec. 2, 2025

(54) TOOTHBRUSH

(71) Applicant: HALEON UK IP LIMITED,
Middlesex (GB)

(72) Inventors: Klaus Reinbold, Middlesex (GB);
Tobias Michel, Middlesex (GB);
Ramona Königsberg, Middlesex (GB)

(73) Assignee: HALEON UK IP LIMITED,
Middlesex (GB)

() Term: 15 Years

(21) Appl. No.: 29/869,126

(22) Filed: Dec. 22, 2022

(30) Foreign Application Priority Data
